28 Claims. (Cl. 155—77)

1

This invention relates to reclining articles of furniture, and more particularly to chairs with a rotatable and tiltable seat, such as office chairs.

An object of the present invention is to provide a tiltable office chair or the like, wherein the springs for returning the seat into its sitting position are invisibly arranged.

A further object of the present invention is to provide a tiltable office chair or the like, wherein the returning springs may be readily adjusted.

Another object of the present invention is to provide a tiltable office chair or the like which is of simple construction and may be readily manufactured at low costs.

A further object of the present invention is to provide a tiltable and rotatable office chair which has a pleasing appearance.

Another object of the present invention is to improve on the construction of tiltable office chairs or the like as now ordinarily made.

Other objects and structural details of the invention will be apparent from the following description when read in conjunction with the accompanying drawings forming part of this specification, wherein:

Fig. 1 is a vertical sectional view of an office chair according to the invention.

Fig. 2 is a sectional view of the chair shown in Fig. 1, wherein, however, the seat is in a reclined position.

Fig. 3 is a fragmentary sectional view of a detail of the chair shown in Figs. 1 and 2.

Fig. 4 is a sectional view taken on line IV—IV of Fig. 1.

Fig. 5 is an elevational view of a detail of the chair shown in Fig. 1, partly in section.

Fig. 6 is a fragmentary sectional view of another embodiment of a chair according to the invention.

Fig. 7 is a fragmentary rear elevational view of the chair shown in Fig. 6.

Fig. 8 is a sectional view of a further embodiment of a chair according to the invention.

Fig. 9 is a fragmentary sectional view of a further embodiment of a chair according to the invention.

Fig. 10 is a sectional view taken on line 10—10 of Fig. 9.

Fig. 11 is a fragmentary sectional view of another embodiment of a chair according to the invention, and

Fig. 12 is a fragmentary rear elevational view of the chair shown in Fig. 11.

Referring now to Figs. 1, 2 and 4, the seat-back-rest structure 1 is mounted on a hollow body or

2

housing 2 forming a part of a pedestal including said housing 2 and legs 3 secured to the latter for carrying same. Casters of any suitable type are arranged on said legs 3. The frame of the seat-back-rest structure 1 as well as the legs 3 of the pedestal 2, 3 are made of tubular material in the embodiment shown in the drawings.

The upper open end of the housing 2 is closed by a thrust-ball-bearing 7 comprising a stationary member 60 and a rotatable member 62. According to Fig. 3 illustrating said arrangement more in detail the stationary member 60 is secured to the housing 2 by screws 61 (only one being shown). A ring 63 having a flange 65 is secured to a projecting flange of the stationary member 60 by screws 67 (only one being shown). The flange 65 of the ring 63 overlapping the rim of the rotatable member 62 prevents an undesired separation of the members 60 and 62 in vertical direction. As shown in Figs. 1, 2 and 4, the rotatable member 62 carries two bearings 8. A rod 9 secured to lugs 64 attached to the frame of the seat-back-rest structure 1 is rotatable in said bearings 8 about a substantially horizontal axis. Thus, the seat-back-rest structure 1 is tiltably mounted on the thrust-bearing 7 at the top of the housing 2.

The rotatable member 62 of the thrust-bearing 7 has an aperture 66 in its center and the stationary member 60 of said thrust bearing has an aperture 68 in its center. A lever 5 rigidly connected with said rod 9 extends downwardly through the passage 66, 68 of the thrust-bearing 7 into the housing 2. One end of a tension spring 4 arranged within said housing 2 is connected to the free end of said lever 5, the other end of said tension spring 4 is connected with an anchoring hook 70 carried by the threaded spindle 72 of an adjusting device 6 mounted in the lower portion of the housing 2. The tension of the spring 4 may be readily adjusted by a longitudinal displacement of the hook 70 by means of the elements of the adjusting device 6. As best shown in Fig. 5, a pin 74 secured to the anchoring hook 70 is in engagement with an annular recess 10 of the spindle 72, so that the hook 70 is rotatable relative to the spindle 72 of the adjusting device 6 and, consequently, the seat 1 may be rotated about the substantially vertical longitudinal axis of the housing 2 without twisting the spring 4.

The sitting position of the seat 1 is limited by an abutment of the lever 5 against the vertical surface 12 of the aperture 66 of the rotatable member 62 of the thrust-bearing 7; the extreme reclined position of the seat 1 is limited by an

abutment of the lever 5 against the inclined surface 76 of said aperture 66. The tapering surface 13 of the aperture 68 of the stationary member 60 of the thrust-bearing 7 may be in alignment with the inclined surface 76 of the aperture 66 of the rotatable member 62 as shown in the drawings.

Intermediate reclined positions may be provided by the adjustable limiting stop 11 mounted on the rotatable member 62 for abutting cooperation with the lever 5.

The operation of the chair shown in Figs. 1-5 is as follows:

Fig. 1 illustrates the chair in the sitting position. When the seat-back-rest structure 1 is tilted by means of the pivot 9 from said sitting position into the extreme reclined position shown in Fig. 2, the spring 4 yieldingly opposes to such a tilting movement of the seat-back-rest structure. A return movement of the seat-back-rest structure into its normal sitting position is assisted by said spring 4. The action of the latter can be adjusted by the adjusting device 6 as desired by the user of the chair.

Irrespective whether the seat of the chair is in the sitting position shown in Fig. 1 or in any more or less tilted position, the seat carried by the thrust-bearing 7 may be rotated relative to the housing 2 about the vertical longitudinal axis of the latter into any desired position. The seat remains always in the same level during such a rotation.

According to the embodiment shown in Figs. 6 and 7, the housing 102 is rotatably mounted on the supporting pedestal 116 by means of a thrust-ball-bearing 107, the member 160 of which is connected with said pedestal 116 and the member 162 of which is connected with the housing 2. Means of the type shown in Fig. 3 may be arranged for preventing a vertical separation of the members 110 and 162. The housing 102 is closed at the top by a member 178 having an aperture 180. The seat 101 is tiltably mounted on said member 178 at 109 at a point spaced from the vertical longitudinal axis of the housing 102. For this purpose a pair of lugs 164 mounted on the frame of the seat 101 are secured to the rod 109 journaled in bearings 108 attached to the member 178. A link 105 swingably mounted on the seat 1 at 114 extends through the aperture 180 into the housing 102.

A structure including rods 118 and a plate 119 is connected with the lower end of the link 105. A plate 121 having bores slidably engaged with said rods 118 is connected to the upper end of a rod 120, the lower end of which is connected with an anchoring hook 170 carried by a spindle 172 of an adjusting device 106 arranged in the lower portion of the housing 102. A compression spring 117 arranged within the housing 102 and interposed between the plates 119 and 121 tends to urge the seat 1 into its sitting position limited by an abutment of a stop 182 arranged on the link 105 against the member 178. The tension of said spring 117 yieldingly opposing a tilting movement of the seat 101 may be adjusted by the adjusting device 106.

The inclined position of the seat 101 may be limited by adjustable stops 111 mounted on projections 113 of the bearings 108 carried by the member 178 closing the rotatable housing 102.

The seat may be rotated together with the housing 102 relative to the pedestal 116 irrespective of its tilting position. Such a rotation has

no influence on the spring 117, as the housing 102 is rotated together with the seat 101.

The thrust-bearing 107 is not under the action of the spring 117, so that its dimensions must be calculated only for the load to be expected by a person resting on the chair.

According to the embodiment shown in Fig. 8, again the housing 202 closed by a member 278 having an aperture 280 is rotatably mounted on the pedestal 216 by means of a thrust-bearing 207. The members 260 and 262 of said bearing 207 may be prevented from vertical separation by suitable means for example of the type shown in Fig. 3. A rod 209 connected with the frame of the seat-back-rest structure 201 by lugs 264 is rotatably mounted in bearings 208 carried by the member 278. Thus, the seat 201 may be tilted on the housing 202 and may be rotated together with the housing.

A lever 222 rigidly connected with the rod 209 extends through the passage 280 of the member 278 into the housing 202. The free end of said lever 222 is in abutting engagement with one arm of a double-armed lever 223 swingably mounted in the housing 202 at 232 at a point substantially in the longitudinal axis of the housing. The other arm of said lever 223 is connected with a rod 224 carrying a holding member 227. A pair of endless bands 226 of rubber or other resilient material is looped around said holding member 227 and another holding member 284 carrying a rod 285 engaged with an anchoring hook 230 carried by an adjusting device 206. Said adjusting device comprises a member 231 having a spherical portion arranged for loose and movable engagement with a spherical recess 228 of a member 225 loosely engaged with gripping means 229 secured to the housing 202. The member 231 of the adjusting device is held in engagement with the member 225 and the latter is held in engagement with the gripping means 229 by the action of the rubber bands 226. The opposing action of said rubber bands to a tilting movement of the seat 201 is stepped up by the double-armed lever 223. The arrangement of the engaged spherical portions of the members 225 and 231 permits the adjusting device 206 to follow the change in the position of the biasing mechanism 224, 227, 226, 284, 285 caused by a rotation of the lever 223 about its pivot 232. The opposing action of said biasing mechanism may be adjusted by the adjusting device 206 by turning a setting knob 286 thereof screwed on the threaded end of the hook 230 and engaged with the lower surface of the member 231.

If desired, the stepping up lever 223 could be replaced by another suitable stepping up mechanism.

The sitting position of the seat 201 is limited by an abutment of the lever 222 against the straight edge of the aperture 280 of the member 278. The reclined or tilted position of the seat 1 is limited by an adjustable stop 233 mounted on the housing 202 for abutting cooperation with said lever 222.

The operation of the chair shown in Fig. 8 is as follows: When the seat 201 is tilted, the lever 222 rigidly connected with the rod 209 actuates the double-armed lever 223 for a swinging movement about its pivot 232. Owing to the stepping up characteristic of said lever 223, the rubber bands 226 are stretched to a larger degree than they would be stretched if they were directly connected to the lever 222, so that the

opposing action of said rubber bands 226 becomes more effective. The seat 201 may be rotated irrespective of the fact whether the seat is in the sitting position or in a tilted position.

According to the embodiment shown in Figs. 9 and 10 the housing 402 open at its top is rotatably mounted on the pedestal 416 by means of the thrust-bearing 415, the members 460 and 462 which may be prevented from vertical separation by suitable means for example of the type shown in Fig. 3. A member 440 secured to a cross-bar 488 attached to the frame of the seat 401 extends into the housing 402. Said member 440 having a cam-portion 441 is swingably mounted on a shaft 438 carried by the housing 402. The end of the cam-portion 441 passes through a slot 490 of the housing 402 when the elements are in the position shown in Fig. 9.

The sitting position of the seat 401 tiltably about the pivot 438 is limited by an abutment of the end of the cam-portion 441 against the upper end of the slot 490; the extreme reclined position of the seat 401 is limited by an abutment of the nose 439 of the member 440 against a flange attached to the upper end of the housing 402.

The cam-portion 441 rigidly connected with the tilttable seat 401 is arranged for slidable engagement with the spherical surface of a member 442 slidably arranged in the housing 402. Said member 442 is under the action of a spring 443 interposed between said member 442 and the plate 444 of an adjusting device 406 arranged on a wall 492 secured to the housing 402. The upper end of the spring 443 is engaged with a cap arranged in the member 442; the lower end of said spring 443 is surrounded by a sleeve carried by the plate 444. The upper end of the spindle of the adjusting device 406 threaded into a threaded bore of the wall 492 bears against the plate 444. Thus, the spring loaded member 442 cooperating with the cam 441 rigidly connected with the seat 401 yieldingly opposes tilting movements of the seat 401.

The tension of the spring 443 may be adjusted by the adjusting device 406. The spring 443 does not act on the thrust-bearing 415, so that the latter is subjected only to the load of the user of the chair.

According to the embodiment shown in Figs. 10 and 11 again the housing 502 covered by a member 578 is rotatably mounted on the pedestal 516 by means of a thrust-bearing 507 of the type described above. The lever 505 rigidly connected with the tilting rod 509 of the seat-structure 501 swingably mounted in the bearings 508 attached to the member 578 extends into the housing 502 wherein it is in engagement with a lug 594 arranged on a member 596 rotatably arranged on a shaft 598 secured to the housing 502. A torsion spring 545 having one of its ends secured to said shaft 598 and having its other end secured to said member 596 tends to hold the lug 594 into engagement with the lever 505. The spring 545 made, for example, of steel or rubber yieldingly opposes tilting movements of the seat 501.

The tilted position of the seat 501 may be limited by an adjustable stop 511 mounted on the housing 502 for cooperation with the lug 594 of the spring-loaded member 596.

The various embodiments of the invention described above show that simple spring devices and housings for enclosing and carrying same may be arranged in many different ways without deviating from the principle of invention. A chair according to the invention may be made of elements light in weight; the chair is comfortable and may be conveniently manipulated. The construction of the chair permits a noiseless rotation and/or tilting of the seat. The chair, also, has a neat appearance.

I have described preferred embodiments of my invention, but it is understood that this disclosure is for the purpose of illustration and that various omissions or changes in shape, proportion and arrangement of parts, as well as the substitution of equivalent elements for those, herein shown and described, may be made without departing from the spirit and scope of the invention as set forth in the appended claims.

What I claim is:

1. A chair comprising: a stationary base-assembly, a rotatable seat-assembly including connecting means and a seat-structure tiltably joined to said connecting means, a thrust-bearing having a stationary member and a rotatable member with annular bearing surfaces, the stationary member of said thrust-bearing being secured to said stationary base-assembly, the rotatable member of said thrust-bearing being in rigid connection with said connecting means of the rotatable seat-assembly, a housing included in one of said two assemblies, and biasing means arranged within said housing, said biasing means being connected to the tilttable seat-structure of said seat-assembly for yieldingly opposing a tilting movement thereof.

2. In a chair as claimed in claim 1, limiting means arranged for abutting cooperation with said tilttable seat-structure so as to limit the extreme reclined position thereof.

3. In a chair as claimed in claim 1, said biasing means having adjusting means associated therewith for adjusting the opposing action thereof.

4. A chair comprising: a base-assembly, a seat-assembly including connecting means and a seat-structure tiltably joined to said connecting means, a thrust-bearing having a stationary member and a rotatable member with annular bearing surfaces, the stationary member of said thrust-bearing being secured to said stationary base-assembly, the rotatable member of said thrust-bearing being in rigid connection with said connecting means of the rotatable seat-assembly, a housing included in one of said two assemblies, a passage in the upper portion of said housing, an element rigidly connected with said seat-structure, said element extending through said passage into said housing, and biasing means arranged within said housing, said biasing means being engaged with said element for yieldingly opposing a tilting movement of said seat-structure.

5. A chair comprising: supporting means, a housing rigidly connected with said supporting means, a thrust-bearing having a stationary member and a rotatable member with annular bearing surfaces, the stationary member of said thrust-bearing being secured to said housing, a seat tiltably mounted on the rotatable member of said thrust-bearing, and biasing means arranged within said housing, said biasing means being connected to said seat for yieldingly opposing a tilting movement thereof.

6. A chair comprising: supporting means, a

housing rigidly connected with said supporting means, a thrust-bearing having a stationary member and a rotatable member, the stationary member of said thrust-bearing being secured to said housing, a seat tiltably mounted on the rotatable member of said thrust-bearing, and biasing means arranged within said housing, said biasing means being connected to said seat for yieldingly opposing a tilting movement thereof.

7. In a chair as claimed in claim 6, said seat and means rigid therewith, forming a tilttable seat-structure, limiting means arranged for abutting cooperation with said tilttable seat-structure so as to limit the extreme reclined position thereof.

8. In a chair as claimed in claim 6, said biasing means having adjusting means associated therewith for adjusting the biasing action thereof.

9. A chair comprising: supporting means, a housing rigidly connected with said supporting means, a thrust-bearing having a stationary member and a rotatable member, the stationary member of said thrust-bearing being secured to said housing, a seat tiltably mounted on the rotatable member of said thrust-bearing, a passage in said thrust-bearing, an element rigidly connected with said seat, said element extending through said passage of the thrust-bearing into said housing, and biasing means arranged within said housing, said biasing means being connected to said element for yieldingly opposing a tilting movement of said seat.

10. In a chair as claimed in claim 9, said housing having an open upper end, and said thrust-bearing covering said open end of said housing.

11. In a chair as claimed in claim 9, limiting means on said thrust-bearing for cooperation with said element so as to limit the extreme tilted position of said seat.

12. In a chair as claimed in claim 9, an adjustable limiting device connected to the rotatable member of the thrust-bearing and arranged for cooperation with said element so as to limit a reclined position of said seat.

13. A chair comprising: supporting means, a housing rigidly connected with said supporting means, a thrust-bearing having a stationary member and a rotatable member, the stationary member of said thrust-bearing being secured to said housing, a seat tiltably mounted on the rotatable member of said thrust-bearing, a passage in said thrust-bearing, an element rigidly connected with said seat, said element extending through said passage of the thrust bearing into said housing, and resilient means arranged within said housing, said resilient means being connected to said housing and to said element for yieldingly opposing a tilting movement of said seat.

14. In a chair as claimed in claim 13, said resilient means including a tension spring, one end of said tension spring being connected to said housing, the other end of said tension spring being connected to said element.

15. In a chair as claimed in claim 13, carrying means arranged at and rigid with the lower portion of said housing, an anchoring element rotatably mounted on said carrying means and extending into said housing, and said resilient means including a tension spring, one end of said tension spring being connected to said anchoring element, the other end of said tension spring being connected to said element.

16. In a chair as claimed in claim 13, carrying means arranged at and rigid with the lower por-

tion of said housing, an adjusting device mounted on said carrying means, an anchoring element rotatable on said adjusting device, and said resilient means including a tension spring, one end of said tension spring being connected to said anchoring element, the other end of said tension spring being connected to said element.

17. A chair comprising: supporting means, a housing rotatably connected with said supporting means for rotation about a vertical axis, a seat tiltably joined to said housing, and biasing means arranged within said housing for acting on said seat so as to yieldingly oppose a tilting movement thereof.

18. In a chair as claimed in claim 17, said rotatable connection comprising a thrust-bearing having a stationary member and a rotatable member, the stationary member being connected to said supporting means, and the rotatable member being connected to said housing.

19. In a chair as claimed in claim 17, limiting means arranged on said housing for cooperation with said seat so as to limit an extreme position thereof.

20. In a chair as claimed in claim 17, said biasing means having adjusting means associated therewith for adjusting the opposing action thereof.

21. A chair comprising: supporting means, a housing rotatably connected with said supporting means for rotation about a vertical axis, said housing having an aperture at its top, a seat tiltably mounted on said housing, an element connected with said seat, said element extending through said aperture into said housing, and resilient means arranged within said housing, said resilient means acting on said element for yieldingly opposing a tilting movement of the seat.

22. In a chair as claimed in claim 21, the tilttable connection between the seat and the housing being at a distance from the axis of rotation of the housing, said element being pivotally connected with said seat, and a spring connected to said housing and said element.

23. A chair comprising: supporting means, a housing rotatably connected with said supporting means for rotation about a vertical axis, said housing having an aperture at its top, a seat tiltably mounted on said housing, an element rigidly connected with said seat, said element extending through said aperture into said housing, stepping up means movably mounted in said housing and engaged with said element, a spring, and an anchoring element movably arranged in said housing, one end of said spring being connected to said stepping up means, and the other end of said spring being connected to said anchoring element.

24. In a chair as claimed in claim 23, a member having a spherical recess arranged in said housing, and said anchoring element having a spherical portion engaging said spherical recess.

25. A chair comprising: supporting means, a housing rotatably connected with said supporting means for rotation about a vertical axis, said housing having an aperture at its top, a seat tiltably mounted on said housing, a cam rigidly connected with said seat, said cam extending into said housing, a member movable in said housing, engaging means mounted in said housing, and a spring in said housing engaged with said engaging means and said member for urging the latter into engagement with said cam.

26. In a chair as claimed in claim 25, said member having a curved surface for cooperation

with said cam, and said engaging means including an adjusting device associated with said spring for adjusting the action thereof.

27. A chair comprising: supporting means, a housing rotatably connected with said supporting means for rotation about a vertical axis, said housing having an aperture at its top, a seat tiltably mounted on said housing, an element rigidly connected with said seat, said element extending through said aperture into said housing, and a spring loaded member swingably arranged in said housing for cooperation with said element so as to yieldingly oppose tilting movements of the seat.

28. A chair comprising: supporting means, a housing rotatably connected with said supporting means for rotation about a vertical axis, said housing having an aperture at its top, a seat tiltably mounted on said housing, an element rigidly connected with said seat, said element extending through said aperture into said housing, a mem-

ber movably arranged in said housing for cooperation with said element said member being in the path of said element upon a tilting movement of said seat, and a torsion spring connected to said housing and said member for yieldingly opposing a tilting movement of said seat upon an engagement of said element with said member.
